SWITCH CONTROL SYSTEM

Earl M. Allen, Swissvale, Pa., assignor to The
Union Switch & Signal Company, Swissvale,
Pa., a corporation of Pennsylvania

Application February 10, 1939, Serial No. 255,719

20 Claims. (Cl. 246—219)

My invention relates to switch control systems, and particularly to improved means for preventing storage of switch control.

It has heretofore been proposed to employ a polarized relay having both neutral and polar contacts to control the motor, either electric or pneumatic, for operating a railway track switch to effect movement of the switch between a normal and a reverse position. It has also been proposed heretofore to provide a control circuit for energizing the polarized relay with current of one or the other relative polarity to thereby operate the relay to control the switch motor, while locking relays or route relays have been provided to interrupt the control circuit and thus prevent the control relay from producing a change in the position of the switch when it is not safe to effect such a change.

If the polarity of the current supplied to the control circuit is changed at a time when the lock relay interrupts the control circuit, no change will be made in the condition of the polarized relay, and therefore, no change will be made in the position occupied by the switch as long as the lock relay remains deenergized.

However, unless some means is provided to prevent such an occurrence, on subsequent energization of the lock relay and picking up of its contacts with resultant completion of the control circuit, the polarized relay will cause the motor to move the switch to the position corresponding to that occupied by the control lever or other mechanism controlling the polarity of the current supplied to the control circuit.

This storage of switch control or delayed movement of the switch may be objectionable and it is desired to provide a switch control system in which storage of switch control is prevented.

It is an object of my invention to provide an improved switch control system in which storage of switch control is prevented.

A further object of my invention is to provide an improved switch control system which is arranged so that on a change in the position of the control lever, unless the switch control relay promptly responds to such movement of the control lever, no change can be effected in the condition of the switch control relay until the control lever is first brought to a position of correspondence with the polar contacts of the relay.

Another object of my invention is to provide an improved switch control system in which no change may be effected in the position of the switch as long as route or locking relays asso-

ciated with the switch are deenergized, and in which no change will occur in the position occupied by the switch on picking up of the contacts of the route or locking relays if the position of the switch control lever has been changed while the locking relays were released.

Another object of my invention is to provide an improved switch control system employing a polarized switch control relay of the retained neutral type, the control system incorporating means controlled by a neutral contact of that relay for controlling energization of the switch control relay in such manner that under usual operating conditions a change in the direction of energization of the polarized relay must take place within the release time of the neutral contacts of the relay or it cannot take place at all.

Another object of my invention is to provide an improved switch control system incorporating a polarized switch control relay and an auxiliary polarized relay together with means controlled by polar contacts of both polar relays for energizing the switch control relay.

A further object of my invention is to provide an improved switch control system employing a polarized switch control relay to control the circuit for energizing the switch motor, the relay having both polar and neutral contacts and the system being arranged so that when the switch is reversed while in transit, the neutral contacts of the polarized relay must become released before the positions of the polar contacts of the relay can be changed to thereby insure that under these conditions the circuit of the switch motor will be interrupted by the neutral contacts of the relay and not by the polar contacts thereof.

Another object of my invention is to provide an improved switch control system.

Other objects of my invention and features of novelty will be apparent from the following description taken in connection with the accompanying drawing.

I shall describe one form of apparatus embodying my invention, and shall then point out the novel features thereof in claims.

In the drawing the single figure is a diagram illustrating one embodiment of the improved switch control system provided by my invention.

Referring to the drawing, the reference character W designates a railway track switch which is movable between a normal and a reverse position by means of an electric motor M. A polarized switch control relay WR is provided to control the motor M. The system includes, in addi-

tion, an auxiliary polarized relay CR, a lock relay LR, and a polarized switch repeating or switch indication relay WRP which cooperate in the manner hereinafter explained to control energization of the switch control relay WR from the control wires 10 and 11.

This system also includes a control lever L which may be located at a point remote from the switch. The lever L is movable between a normal position and a reverse position to effect the supply of current of one or the other relative polarity to the control wires 10 and 11.

The lever L has associated therewith contacts 14 and 15 which are movable in accordance with movement of the lever L. The contact 14 is constantly connected to terminal B of battery 16, while contact 15 is constantly connected to terminal C of battery 16.

When the lever L is in the normal position, as shown, contact 14 engages a stationary contact to which is connected control wire 10, while contact 15 engages a stationary contact to which is connected control wire 11 so that current of one relative polarity, which may be considered normal polarity, is supplied from battery 16 to the control wires 10 and 11.

Similarly, when the control lever L is in the reverse position, contact 14 engages a stationary contact to which is connected the control wire 11, while contact 15 engages a stationary contact to which is connected a branch of control wire 10 so that current of the opposite or reverse relative polarity is supplied from battery 16 to the control wires 10 and 11.

The switch W has associated therewith contacts 17, 18, 19, and 20 which are movable in accordance with movement of the switch W to control the switch repeating relay WRP, and to also control the circuit of the switch motor M.

Control wire 10 is connected to one terminal of the winding of switch control relay WR, while a branch of wire 10 is connected to one terminal of the winding of the auxiliary polarized control relay CR. The control wire 11 is connected to front contact 22 of lock relay LR, while a branch of control wire 11 is connected to a terminal of the winding of relay CR.

The lock relay LR has a movable contact 24 which when picked up engages contact 22, while contact 24 is connected by wire 26 to neutral contact 27 of switch control relay WR, and also to polar contact 28 of control relay CR. The other terminal of the winding of relay WR is connected by wire 30 to a polar contact 31 of relay WR, and to neutral contact 33 of switch repeating relay WRP.

Contact 28 of auxiliary relay CR, when in the normal position as shown, engages a stationary contact 35 which is connected by wire 36 to contact 37 which is engaged by polar contact 31 of relay WR when that contact is in its normal position as shown.

Contact 28 of relay CR, when in its reverse position, engages a stationary contact 40 which is connected by wire 41 to contact 43 which is engaged by polar contact 31 of relay WR when that contact is in its reverse position.

Contact 27 of relay WR when picked up engages a contact 45 which is connected by wire 46 to a contact 47, while contact 47 is engaged by contact 33 of relay WRP when contact 33 is picked up.

Contact 27 of relay WR when released engages a stationary contact 48 which is connected by wire 50 to a contact 51, while contact 51 is en-

gaged by movable contact 33 of relay WRP when contact 33 is released.

It will be seen that when the positions of the polar contacts of the relays WR and CR are in agreement and the contact of the lock relay LR is picked up, a circuit is established to energize the winding of the switch control relay WR from the control wires 10 and 11.

Thus when the polar contacts of both relays CR and WR are in their normal positions, as shown, and contact 24 of relay LR is picked up, a circuit is established from control wire 11 to one terminal of the winding of relay WR. This circuit is traced from wire 11 through contacts 22-24 of lock relay LR, wire 26, contacts 29-35 of relay CR, wire 36, contacts 37-31 of relay WR, and wire 30 to one terminal of the winding of relay WR, the other terminal of which has control wire 10 connected thereto.

Similarly, when the polar contacts of both relays CR and WR are in their reverse positions and contact 24 of relay LR is picked up, a circuit is established from wire 11 to one terminal of the winding of relay WR. This circuit is traced from wire 11 through contacts 22-24 of relay LR, wire 26, contacts 28-40 of relay CR, wire 41, contacts 43-31 of relay WR, and wire 30 to one terminal of the winding of relay WR, the other terminal of which has control wire 10 connected thereto.

A circuit is also established to energize the winding of relay WR from the control wires 10 and 11 when the neutral contacts of both relays WR and WRP are picked up or released.

Thus when contact 27 of relay WR and contact 33 of relay WRP are both picked up, assuming the contact 24 of lock relay LR is also picked up, a circuit is established from control wire 11 to one terminal of the winding of relay WR. This circuit is traced from wire 11 through contacts 22-24 of relay LR, wire 26, contacts 27-45 of relay WR, wire 46, contacts 47-33 of relay WRP, and wire 30 to one terminal of the winding of relay WR, while the other terminal of the relay winding has control wire 10 connected thereto.

Similarly, when contact 27 of relay WR and contact 33 of relay WRP are both released, a circuit is established to energize the winding of relay WR from the control wires 10 and 11 providing contact 24 of lock relay LR is picked up. This circuit is traced from wire 11 through contacts 22-24 of relay LR, wire 26, contacts 27-43 of relay WR, wire 50, contacts 51-33 of relay WRP, wire 30, winding of relay WR, and control wire 10.

The polar contact 55 of relay WR and the switch operated contacts 17, 18, and 19 cooperate to control the supply of current to the polarized switch repeating relay WRP from a battery 56.

Polar contact 55 of relay WR is connected by wire 58 to one terminal of the winding of relay WRP, while the other terminal of the winding of relay WRP is connected by wire 59 to switch operated contact 17. Contact 55 when in the normal position, as shown, engages a contact 60 which is connected by wire 62 to switch operated contact 18, while contact 55 when in the reverse position engages polar contact 63 which is connected by wire 64 to switch operated contact 19.

Switch operated contact 17 engages a stationary contact 65 when and only when the switch W is in the normal position, while contact 17 engages a stationary contact 67 when and only

when the switch W is in the reverse position. Contact 65 is connected by wire 69 to terminal C of battery 56, while contact 67 is connected by wire 70 to terminal B of battery 56.

5. Switch operated contact 18 engages a stationary contact 12 when and only when the switch W is in the normal position, while contact 72 has connected thereto a branch of wire 70 leading from terminal B of battery 56.
10. Similarly switch operated contact 19 engages a stationary contact 73 when and only when the switch W is in the reverse position, while contact 73 has connected thereto a branch of wire 69 leading from terminal C of battery 56.

15. Although the switch operated contacts 17, 18, and 19 have been described as engaging the stationary contacts associated therewith when the switch is in its normal or its reverse position, it is contemplated that these contacts may be arranged to engage when and only when the switch is in its normal or reverse position and is locked in that position.

The neutral and polar contacts of relay WR and switch operated contact 20 cooperate to control the energizing circuits of the switch motor M. The neutral contacts 75 of relay WR, when picked up, engage stationary contacts 76 to which are connected a branch of wire 70 leading from terminal B of battery 56. Neutral contacts 75 are connected by wire 77 to normal polar contact 78 and reverse polar contact 79.

Relay WR has a polar contact 80 which is connected by wire 81 to one brush of the motor armature 82, while the relay has another polar contact 84 which is connected by wire 85 to the other brush of the motor armature.

Polar contact 80, when in the normal position, as shown, engages a contact 87 which is connected by wire 88 to contact 90 associated with switch operated contact 20, while contact 80 when in the reverse position engages contact 79.

Contact 84, when in the normal position, as shown, engages contact 78, while when it is in the reverse position, it engages a contact 91 which is connected by wire 92 to contact 94 associated with the switch operated contact 20.

Switch operated contact 20 is connected by wire 95 to one terminal of the motor field winding 96, the other terminal of which is connected to terminal C of battery 56. Contact 20 engages contact 94 in all positions of the switch W except the reverse position thereof, while contact 20 engages contact 90 in all positions of the switch W except the normal position thereof.

The relay WR is of the retained neutral polar type, that is, on reversal in the direction of energization of the relay winding the neutral contacts of the relay will remain picked up while the polar contacts change from one position to the other.

The polarized auxiliary control relay CR is designed so that on a change in the direction of energization of the relay winding the polar contacts of this relay will shift from one position to the other much more rapidly than the polar contacts of relay WR change their positions.

The neutral contact 33 of the polarized switch repeating relay WRP is slow in releasing so that when the contact is picked up, it will remain picked up for a time interval after interruption of the circuit of the relay winding.

The polarized switch repeating relay WRP has 75 in addition to the neutral contact 33 a neutral

contact 100 and a polar contact 101 which are connected by a wire 102. Contact 100 when picked up engages contact 103 to which is connected wire 104. Contact 101 when in the normal position, as shown, engages contact 106 to 5 which is connected wire 107, while when contact 101 is in the reverse position, it engages contact 109 to which is connected wire 110. The circuits established by the wires 104, 107 and 110 may be employed in any manner well-known 10 in the art to indicate the position occupied by the switch W.

The winding of the lock relay LR is energized by current supplied over a circuit controlled by traffic conditions in the vicinity of 15 the switch W in the manner well-known in the art so that the winding of relay LR is energized only when it is safe to effect the change in the position of the switch W, while the relay LR is deenergized at all other times.

The equipment is shown in the drawing in the position which it assumes when the control lever L and the switch W are in their reverse positions, and when the lock relay LR is energized.

As the control lever L is in the normal position, current of normal relative polarity is supplied from battery 16 to control wires 10 and 11 and the windings of relays CR and WR are energized with the result that the polar contacts of these relays are in their normal positions, as shown, while the neutral contacts of relay WR are picked up.

The winding of relay CR is energized directly from the control wires 10 and 11, while the circuit 35 for energizing the winding of relay WR is traced from wire 11 through contacts 22-24 of relay LR, wire 26, contacts 28-35 of relay CR, wire 36, contacts 37-31 of relay WR, wire 30, winding of relay WR, and control wire 10.

As the polar contacts of relay WR are in their normal positions and as the switch W is also in the normal position, a circuit is established to energize the switch repeating relay WR with current of normal relative polarity.

This circuit is traced from terminal B of battery 56 through wire 70, contact 72, switch operated contact 18, wire 62, contacts 60-55 of relay WR, wire 53, winding of relay WRP, wire 59, switch operated contact 17, contact 65, and wire 69 to terminal C of battery 56.

As the winding of relay WRP is energized, contact 33 is picked up, and as contact 27 of relay WR is picked up at this time, a circuit is established by contacts 27 and 33 to connect control wire 11 to a terminal of the winding of relay WR. This circuit is traced from wire 11 through contacts 22-24 of relay LR, wire 26, contacts 27-45 of relay WR, wire 46, contacts 47-33 of relay WRP, and wire 39 to a terminal of the 60 winding of relay WR.

At this time the neutral and polar contacts of the relay WR establish a circuit for the switch motor M to cause the motor to move the switch W to the normal position, but as the switch W is in the normal position contact 29 is out of engagement with the contact 90 with the result that the switch motor circuit is interrupted.

If at this time the operator wishes to effect movement of the switch W from the normal to 70 the reverse position, he may do so by moving the lever L from its normal to its reverse position, thereby effecting the supply of current of reverse relative polarity from battery 16 to the control wires 10 and 11.

On the supply of current of reverse relative polarity to the control wires 10 and 11 polar contact 28 of auxiliary control relay CR is promptly shifted from its normal to its reverse position. On this movement of contact 28 one circuit for energizing the winding of the control relay WR from the control wires 10 and 11 is interrupted by movement of contact 28 out of engagement with contact 35. However, at this time the winding of relay WR continues to be energized from control wires 10 and 11 by means of the circuit established by contact 27 of relay WR and contact 33 of relay WRP.

In addition, upon the supply of current of reverse relative polarity to the control wires 10 and 11 the polar contacts of the relay WR are shifted from their normal to their reverse positions, but, as previously explained, since the relay CR is much faster operating than the relay WR, the contacts of relay WR do not complete their movement until after contact 28 of relay CR has completed its movement.

Because of the retained neutral characteristic of the relay WR, on reversal of the direction of energization of the winding of the relay with consequent change in the position of the polar contacts of the relay, the neutral contacts 27 and 75 of the relay remain picked up, and the contact 27 maintains the circuit for energizing the winding of relay WR from the control wires 10 and 11 until the polar contacts of relay WR and relay CR have both completed their movement from the normal to the reverse position.

When contact 28 of relay CR and contact 31 of relay WR have both moved to the reverse position, the circuit controlled by these contacts for energizing the winding of relay WR from control wires 10 and 11 is again complete with the result that the winding of relay WR continues to be energized from the control wires 10 and 11 after contact 33 of relay WRP becomes released, which occurs on movement of polar contact 55 of relay WR away from the normal position. Because of the slow releasing characteristic of the neutral contacts of relay WRP, contact 33 will remain picked up for long enough after movement of contact 55 out of engagement with contact 60 to insure that the polar contacts of relay WR will complete their movement so that contact 50 31 will reestablish the circuit of the relay winding.

On movement of the polar contacts 80 and 84 of relay WR from their normal to their reverse positions the normal supply circuit for the motor M is interrupted and the reverse supply circuit 55 for the switch motor is established.

The reverse supply circuit for the motor M is traced from terminal B of battery 56 through wire 70, contacts 76-75 of relay WR, wire 77, reverse polar contacts 79-80 of relay WR, wire 81, motor armature 82, wire 85, reverse polar contacts 84-91 of relay WR, wire 92, contact 94, switch operated contact 20, wire 95, motor field winding 96, and terminal C of battery 56.

On movement of the switch W away from the normal position contacts 17 and 18 are moved out of engagement with contacts 65 and 72, respectively, while when the switch W is moved to the reverse position, contact 20 is moved out of engagement with contact 94 to thereby interrupt the reverse supply circuit for the switch motor M. In addition, on movement of the switch W to the reverse position contact 17 is moved into engagement with contact 67, while contact 19 is moved into engagement with contact 73 to thereby establish a circuit for energizing

the winding of relay WRP. This circuit is traced from terminal B of battery 56 through wire 70, contact 67, switch operated contact 17, wire 59, winding of relay WRP, wire 58, reverse polar contacts 55-63 of relay WR, wire 64, 5 switch operated contact 19, contact 73, and wire 69 to terminal C of battery 76.

On energization of the winding of relay WRP contact 33 of the relay is again picked up to re-establish the circuit controlled thereby. However, at this time the winding of the relay WR is energized from the control wires 10 and 11 over the circuit which includes polar contact 28 of relay CR and polar contact 31 of relay WR so that picking up of contact 33 of relay WRP has 15 no significance.

In a similar manner, if while the switch W is in the reverse position the operator desires to effect movement of the switch to the normal position, he may do so by moving the lever L from 20 the reverse to the normal position, thereby again effecting the supply of current of normal relative polarity to the control wires 10 and 11.

On the supply of current of normal relative polarity to the control wires 10 and 11 the polar contact 28 of relay CR is shifted from the reverse to the normal position, and on this movement of the contact 28 the circuit controlled thereby for energizing the winding of relay WR from the control wires 10 and 11 is interrupted. 30

However, at this time contact 27 of relay WR and contact 33 of relay WRP remain picked up and maintain the circuit which they control for energizing the winding of relay WR from the control wires 10 and 11. Accordingly, the winding of relay WR is energized with current of normal relative polarity with the result that the polar contacts of relay WR are shifted from the reverse to their normal positions, and on movement of contact 31 of relay WR to the normal 40 position the circuit controlled by contact 31 and contact 28 of relay CR is again complete so that the winding of relay WR continues to be energized from control wires 10 and 11 after contact 33 of relay WRP becomes released. 45

On movement of the polar contacts of relay WR from their reverse to their normal positions contact 55 is shifted out of engagement with contact 63, thereby interrupting the circuit for energizing the winding of relay WRP. Because of the slow releasing characteristic of contact 33 of relay WRP this contact does not release instantaneously, but remains picked up until after the polar contacts of the relay WR have completed their movement so that contact 31 completes the 55 circuit for energizing the winding of relay WR from the control wires 10 and 11 before contact 33 of relay WRP becomes released.

In addition, upon movement of the polar contacts of relay WR from their reverse to their 60 normal positions the reverse supply circuit of the switch motor M is interrupted and the normal supply circuit for the motor is established to cause the motor to move the switch from the reverse to the normal position. 65

The normal supply circuit is traced from terminal B of battery 56 through wire 70, contacts 76-75 of relay WR, wire 77, normal polar contacts 78-84 of relay WR, wire 85, motor armature 82, wire 86, normal polar contacts 80-87 of 70 relay WR, wire 88, contact 90, switch operated contact 20, wire 95, motor field winding 96, and terminal C of battery 56.

When the switch W completes its movement to the normal position, contact 20 is moved out of 75

engagement with contact 30, thereby interrupting the normal supply circuit for the switch motor M with the result that the motor no longer is energized.

5 In addition, on completion of movement of the switch W to the normal position switch operated contact 18 is moved into engagement with contact 72, while switch operated contact 17 is moved into engagement with contact 65 to thereby establish the circuit for energizing the winding of relay WRP. This circuit is traced from terminal B of battery 56 through wire 70, contact 72, switch operated contact 18, wire 62, normal polar contacts 60—65 of relay WR, wire 58, winding 15 of relay WRP, wire 59, switch operated contact 17, contact 65, wire 68 to terminal C of battery 56.

On energization of the winding of relay WRP contact 33 of the relay again becomes picked up, 20 but as the winding of relay WR is energized at this time by current supplied from the control wires 10 and 11 over the circuit established by polar contact 28 of relay CR and polar contact 31 of relay WR, picking up of contact 33 is with- 25 cut result.

From the foregoing it will be seen that under normal conditions on a change in the polarity of the current supplied to the control wires 10 and 11 a circuit controlled by the polar contacts 30 of relays CR and WR for energizing the winding of the relay WR from the control wires 10 and 11 is momentarily interrupted during movement of these contacts from one position to the other. However, at this time a circuit for energizing 35 the winding of relay WR from the control wires 10 and 11 is temporarily maintained by the circuit controlled by neutral contact 27 of relay WR and neutral contact 33 of relay WRP so that the winding of relay WR is continuously energized from the control wires 10 and 11 during movement of the polar contacts of relays CR and WR.

When the polar contacts of relays CR and WR complete their movement, they reestablish the 45 circuit controlled thereby for energizing the winding of the relay WR from the control wires 10 and 11 so that the winding of relay WR remains energized after contact 33 of relay WRP becomes released.

50 Under normal operating conditions, therefore, on a change in the polarity of the current supplied to the control wires 10 and 11 the winding of relay WR remains continuously connected to the control wires 10 and 11 and the polar contacts 55 of the relay WR are shifted from one position to the other to complete the normal or reverse supply circuit for the switch motor M.

The system provided by my invention is arranged so that if the polarity of the current supplied to the control wires 10 and 11 is changed at a time when the switch W is in transit between one of its positions and the other, the polar contacts of the relay WR will remain in the position which they occupy, while the neutral contacts 60 of the relay become released and thus interrupt the circuit of the switch motor. Thereafter the polar contacts of relay WR will shift from one position to the other and subsequently the neutral contacts of the relay will become picked up to 65 reestablish the motor circuit.

This sequence of operation of the contacts of the relay WR at this time is desirable as it insures that the circuit of the switch motor will be interrupted by the neutral contacts, which are 70 adapted for this service, and not by the polar

contacts of the relay, which are not adapted for such service.

For purposes of illustration it will be assumed that the switch W is being moved from the normal to the reverse position and that before 5 the switch attains the reverse position the operator decides to return the switch to the normal position.

In order to effect movement of the switch W to the reverse position the operator moves the 10 control lever L from the normal to the reverse position, thereby effecting the supply of current of reverse relative polarity to the control wires 10 and 11. At this time the relays CR and WR operate as previously described in detail and the 15 polar contacts of the relay WR establish the reverse supply circuit for the motor M to cause the motor M to move the switch W towards the reverse position, while contact 28 of relay CR and contact 31 of relay WR cooperate to establish the 20 circuit for energizing the winding of relay WR from the control wires 10 and 11.

In addition, polar contact 55 of relay WR interrupts the circuit of the winding of relay WRP so that contact 33 of this relay becomes released 25 and engages its back point of contact. The circuit of the winding of relay WRP is additionally interrupted by switch operated contacts 17 and 18 on movement of the switch W away from the 30 normal position.

When the operator decides to return the switch W to the normal position, he returns the control lever L to the normal position, thereby again effecting the supply of current of normal relative polarity to the control wires 10 and 11. On the 35 supply of current of this polarity to control wires 10 and 11 contact 28 of relay CR is shifted from its reverse to its normal position. As previously explained, contact 28 of relay CR operates very quickly with the result that it is moved out of 40 engagement with contact 40 to thereby interrupt the circuit of the winding of relay WR before the winding of relay WR has been energized sufficiently with current of normal relative polarity to effect movement of polar contact 31 from its reverse to its normal position. Accordingly, contact 31 and the other polar contacts of relay WR remain in their reverse positions and the reverse supply circuit for the motor is not interrupted 45 by the polar contacts of relay WR. 50

On movement of contact 28 of relay CR to the normal position at a time when polar contact 31 of relay WR is in the reverse position the circuit controlled by these contacts for energizing the winding of relay WR from control wires 10 and 55 11 is interrupted.

Furthermore, at this time as contact 33 of relay WRP is released, while neutral contact 27 of relay WR is momentarily held picked up, no circuit is established by these contacts to energize 60 the winding of relay WR from the control wires 10 and 11. The winding of relay WR, therefore, is deenergized.

After a short time interval the neutral contacts of relay WR become released and contacts 75 interrupt the reverse supply circuit for the motor M while contact 27 engages contact 48. At this time, as contact 33 of relay WRP is in engagement with contact 51, a circuit is established to energize the winding of relay WR from control wires 10 and 11, this circuit being traced from wire 11 through contacts 22—24 of relay LR, wire 26, contacts 21—48 of relay WR, wire 50, contacts 51—33 of relay WRP, and wire 30 to one terminal of the winding of relay WR, while 70 75

the other terminal of this winding is connected to control wire 10.

Accordingly, on release of contact 27 of relay WR the winding of the relay WR becomes energized with current of normal relative polarity supplied from the control wires 10 and 11. The operating characteristics of relay WR are such that on energization of its winding the polar contacts of the relay will shift from their reverse to their normal positions before the winding of the relay has been energized to a degree sufficient to effect picking up of the neutral contacts of the relay. Accordingly, the polar contacts of the relay WR will be shifted from their normal to their reverse positions as a result of energization of the winding of relay WR by current supplied over back contact 48 of the relay. The normal supply circuit for the switch motor M is not complete on this movement of the polar contacts of relay WR since the neutral contacts 75 of the relay remain released.

When the polar contact 31 of relay WR is shifted from the reverse to the normal position, it is again in agreement with the position occupied by the polar contact 28 of relay CR and the circuit controlled by the polar contact 28 of relay CR and the polar contact 31 of relay WR for energizing the winding of relay WR from control wires 10 and 11 is again complete.

The neutral contacts 27 and 75 of the relay WR now become picked up. On picking up of contact 27 and movement of this contact out of engagement with contact 48 to interrupt the circuit controlled by contact 27 for energizing the winding of relay WR, the winding of relay WR does not become deenergized, but continues to be energized by current supplied over the circuit controlled by polar contact 28 of relay CR and polar contact 31 of relay WR.

On picking up of the neutral contacts 75 of the relay WR at a time when the polar contacts of the relay are in their normal positions, the normal supply circuit for the switch motor M is again complete and this motor is operated to return the switch W to the normal position. When the switch attains the normal position, the contact 20 is moved out of engagement with contact 90 to interrupt the normal supply circuit for the switch motor M, while contacts 17 and 18 establish the circuit for energizing the winding of relay WRP.

The system operates in a similar manner if while the switch W is being moved towards the normal position the operator decides to return the switch W to the reverse position.

When the switch W is in transit, the contact 33 of relay WRP is released and interrupts the circuit controlled by this contact and by contact 27 of relay WR for energizing the winding of relay WR during movement of the polar contacts of relays CR and WR from one position to the other.

On the supply of current of reverse relative polarity to the control wires 10 and 11 at a time when the switch W is being moved to the normal position, contact 28 of relay CR is promptly shifted to the reverse position, thereby interrupting the circuit for energizing the winding of relay WR from the control wires 10 and 11. Accordingly, the neutral contacts of relay WR become released and interrupt the normal supply circuit for the switch motor M, while contact 27, when released, cooperates with contact 33 of relay WRP to establish a circuit for energizing the

winding of relay WR from the control wires 10 and 11.

As current of reverse relative polarity is supplied to the control wires 10 and 11 at this time, the polar contacts of relay WR will be shifted to their reverse position and contact 31 will be in correspondence with contact 28 of relay CR, and these contacts will establish a circuit for energizing the winding of relay WR from the control wires 10 and 11. Subsequently the neutral contacts of relay WR become picked up and complete the reverse supply circuit for the motor M.

The system provided by my invention is arranged so that when the contact 24 of the lock relay LR is released, the circuit for energizing the winding of the relay WR is interrupted and cannot be completed as long as contact 24 remains released. As the winding of relay WR is deenergized when the contact of the lock relay LR is released, the neutral contacts 75 of relay WR are released and interrupt the circuit of the switch motor M with the result that the motor M is deenergized and cannot be energized as long as the contact 24 of the lock relay LR remains released.

Thus it will be seen that when the contact of the lock relay LR is released, no connection is established from control wire 11 to wire 26, and hence even if a circuit is established by polar contact 28 of relay CR and polar contact 31 of relay WR, or by neutral contact 27 of relay WR and neutral contact 33 of relay WRP, from wire 36 to wire 30 leading to a terminal of the winding of relay WR, the winding of relay WR will not be energized and the neutral contacts of this relay will remain released.

If while the contact 24 of lock relay LR is released the control lever L is moved from one position to the other, thereby effecting a change in the polarity of the current supplied to the control wires 10 and 11, the relay WR will not be affected since, as explained above, the connection from the control wire 11 to the relay winding is interrupted at this time.

The system provided by my invention is also arranged so that if the position of the control lever L is changed while the contact 24 of the lock relay LR is released, no change will take place in the condition of the relay WR on subsequent picking up of the lock relay contact at a time when the control lever and the polar contacts of the relay WR are out of correspondence.

It will be seen that the winding of the auxiliary control relay CR is energized from the control wires 10 and 11 by a circuit independent of the lock relay LR so that the contact 28 of the relay CR responds to changes in the polarity of the current supplied to the control wires 10 and 11 both when the lock relay LR is deenergized and when it is energized.

For purposes of illustration, it will be assumed that the contact of the lock relay becomes released at a time when the control lever L and the switch W are in their normal positions, and that while the lock relay LR is deenergized, the control lever L is shifted to the reverse position.

On release of the contacts of the lock relay LR at a time when the winding of relay WR is energized with current of normal relative polarity, the winding of relay WR is deenergized, as explained above, and the neutral contacts 27 and 75 of the relay become released, while the polar contacts of the relay remain in their normal positions.

At this time as the switch W is in the normal position, the switch operated contacts 17 and 18 establish a circuit to energize the winding of relay WRP with the result that contact 33 of relay WRP is picked up. As contact 33 of relay WRP is picked up, and as contact 27 of relay WR is released, these contacts do not establish a circuit to connect control wire 26 to wire 30.

On movement of the control lever L to the reverse position and resultant supply of current of reverse relative polarity to the control wires 10 and 11 the polar contact 28 of relay CR is shifted from the normal to the reverse position, thereby interrupting the circuit controlled jointly by this contact and by polar contact 31 of relay WR for establishing connection from wire 26 to wire 30.

It will be seen that at this time both circuits for establishing connection from wire 26 to wire 30 are interrupted. Accordingly, on subsequent picking up of the contact 24 of lock relay LR with resultant completion of the circuit from control wire 11 to wire 26 the winding of relay WR does not become energized since no connection is established from wire 26 to wire 30 leading to one terminal of the winding of relay WR.

The winding of relay WR, therefore, remains deenergized and the neutral contacts of the relay remain released, while the polar contacts of relay WR remain in their normal positions. As the neutral contacts of relay WR are released, the circuit of the switch motor M is interrupted and the switch W will remain in the normal position.

35 The operator may regain control of the switch W by returning the control lever L to the normal position, that is, to a position in correspondence with the polar contacts of relay WR.

On movement of control lever L to the normal position current of normal relative polarity is again supplied to the control wires 10 and 11 with the result that contact 28 of relay CR is shifted from the reverse to the normal position.

On movement of contact 28 to the normal position at a time when polar contact 31 of relay WR is also in the normal position the circuit controlled by these contacts for establishing connection from wire 26 to wire 30 is again complete. As the circuit from wire 26 to wire 30 is now complete, and as it is assumed that the contact 24 of lock relay LR is picked up, the circuit for energizing the winding of relay WR from the control wires 10 and 11 is complete and this winding is energized with current of normal relative polarity.

On energization of the winding of relay WR with current of normal relative polarity the neutral contacts of the relay become picked up, while the polar contacts of the relay remain in their normal positions. On picking up of neutral contact 27 of relay WR the circuit controlled by this contact and by neutral contact 33 of relay WRP for energizing the winding of relay WR is again complete.

65 If the operator now desires to effect movement of the switch W to the reverse position, he may do so by moving the control lever L from the normal to the reverse position, thereby effecting the supply of current of reverse relative polarity to the control wires 10 and 11, while the equipment will operate in the manner previously described in detail and the motor M will drive the switch W to the reverse position.

The system operates in substantially the same manner if while the control lever L and the

switch W are in their reverse positions the contact of the lock relay LR becomes released, and if while the lock relay contact 24 is released the control lever L is shifted to the normal position. Under such circumstances, no change will take place in the condition of the relay WR on subsequent picking up of the contact of the lock relay LR.

The operator, however, may regain control of the switch W by returning the control lever L to the reverse position, that is, to the position corresponding to the position occupied by the polar contacts of relay WR.

Although I have herein shown and described only one form of switch control system embodying my invention, it is understood that various changes and modifications may be made therein within the scope of the appended claims without departing from the spirit and scope of my invention.

Having thus described my invention, what I claim is:

1. In a switch control system, in combination, a railway track switch movable between a normal and a reverse position, a motor for moving said switch, a polarized switch control relay operative when its winding is energized with current of one relative polarity to condition the motor to move the switch to its normal position, said relay being operative when its winding is energized with current of the opposite relative polarity to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by the neutral contact of the switch control relay and by the neutral contact of the indication relay for energizing the winding of the switch control relay from said control wires, a circuit controlled by a polar contact of the switch control relay for also energizing the winding of the switch control relay from said control wires, and a lock relay governed by traffic conditions in the vicinity of the switch and controlling the circuit of the switch control relay winding.

2. In a switch control system, in combination, a railway track switch movable between a normal and a reverse position, a motor for moving said switch, a polarized switch control relay operative when its winding is energized with current of one relative polarity to condition the motor to move the switch to its normal position, said relay being operative when its winding is energized with current of the opposite relative polarity to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by the neutral contact of the switch control relay and by the neutral contact of the indication relay for energizing the winding of the switch control relay from said control wires, a circuit controlled by a polar contact of the switch control relay for also energizing the winding of the switch control relay from said control wires, and a lock relay governed by traffic conditions in the vicinity of the switch and controlling the circuit of the switch control relay winding.

- position for energizing the winding of the indication relay, a pair of control wires, means for selectively supplying to said control wires current of one or the other relative polarity, a circuit controlled by the neutral contact of the switch control relay and by the neutral contact of the indication relay for energizing the winding of the switch control relay from said control wires, an auxiliary polarized relay having a winding constantly energized from said control wires, a circuit controlled jointly by a polar contact of said auxiliary relay and by a polar contact of the switch control relay for also energizing the winding of the switch control relay from said control wires, and a lock relay governed by traffic conditions in the vicinity of the switch and controlling the circuit of the switch control relay winding.
3. In a switch control system, in combination, a railway track switch movable between a normal and a reverse position, a motor for moving said switch, a polarized switch control relay operative when its winding is energized with current of one relative polarity to condition the motor to move the switch to its normal position, said relay being operative when its winding is energized with current of the opposite relative polarity to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by the neutral contact of the switch control relay and by the neutral contact of the indication relay for energizing the winding of the switch control relay from said control wires, said circuit being complete when and only when both of said contacts are released or when both of said contacts are picked up, a circuit controlled by a polar contact of the switch control relay for also energizing the winding of the switch control relay from said control wires, and a lock relay governed by traffic conditions in the vicinity of the switch and controlling the circuit of the switch control relay winding.
4. In a switch control system, in combination, a railway track switch movable between a normal and a reverse position, a motor for moving said switch, a polarized switch control relay operative when its winding is energized with current of one relative polarity to condition the motor to move the switch to its normal position, said relay being operative when its winding is energized with current of the opposite relative polarity to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for

selectively supplying to said control wires current of one or the other relative polarity, a circuit controlled by the neutral contact of the switch control relay and by the neutral contact of the indication relay for energizing the winding of the switch control relay from said control wires, an auxiliary polarized relay having a winding constantly energized from said control wires, a circuit controlled jointly by a polar contact of said auxiliary relay and by a polar contact of the switch control relay for also energizing the winding of the switch control relay from said control wires, said circuit being complete when and only when the polar contacts of both relays are in their normal positions or when the polar contacts of both relays are in their reverse positions, and a lock relay governed by traffic conditions in the vicinity of the switch and controlling the circuit of the switch control relay winding.

5. In a switch control system, in combination, a railway track switch movable between a normal and a reverse position, a motor for moving said switch, a polarized switch control relay operative when its winding is energized with current of one relative polarity to condition the motor to move the switch to its normal position, said relay being operative when its winding is energized with current of the opposite relative polarity to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by the neutral contact of the switch control relay and by the neutral contact of the indication relay for energizing the winding of the switch control relay from said control wires, said circuit being complete when and only when both of said contacts are released or when both of said contacts are picked up, a circuit controlled by a polar contact of the switch control relay for also energizing the winding of the switch control relay from said control wires, and a lock relay governed by traffic conditions in the vicinity of the switch and controlling the circuit of the switch control relay winding.

6. In a switch control system, in combination, a railway track switch movable between a normal and a reverse position, an electric motor for operating said switch, a polarized switch control relay having neutral and polar contacts, the neutral contacts being picked up when the relay winding is energized with current of either polarity and when picked up remaining picked up for a time interval subsequent to interruption of the circuit of the relay winding, a neutral contact of said relay controlling the supply circuit for energizing said motor, said neutral contact when picked up establishing said supply circuit and when released interrupting said supply circuit, the

- polar contacts of said relay being operative when the relay winding is energized with current of one relative polarity to energize the motor from said supply circuit so as to cause the motor to move the switch to one position, the polar contacts of said relay being operative when the relay winding is energized with current of the opposite relative polarity to energize the motor from said supply circuit so as to cause the motor to move the switch to its other position, an indication relay having a slow releasing neutral contact, means operable when and only when the switch is in either its normal or its reverse position for energizing the winding of said indication relay, a pair of control wires, means for selectively supplying to said control wires current of one or the other relative polarity, and a circuit controlled by a neutral contact of the switch control relay and by the neutral contact of the indication relay for energizing the winding of the switch control relay from said control wires.
7. In a switch control system, in combination, a railway track switch movable between a normal and a reverse position, an electric motor for operating said switch, a polarized switch control relay having neutral and polar contacts, the neutral contacts being picked up when the relay winding is energized with current of either polarity and when picked up remaining picked up for a time interval subsequent to interruption of the circuit of the relay winding, a neutral contact of said relay controlling the supply circuit for energizing said motor, said neutral contact when picked up establishing said supply circuit and when released interrupting said supply circuit, the polar contacts of said relay being operative when the relay winding is energized with current of one relative polarity to energize the motor from said supply circuit so as to cause the motor to move the switch to one position, the polar contacts of said relay being operative when the relay winding is energized with current of the opposite relative polarity to energize the motor from said supply circuit so as to cause the motor to move the switch to its other position, an indication relay having a slow releasing neutral contact, means operable when and only when the switch is in either its normal or its reverse position for energizing the winding of said indication relay, a pair of control wires, means for selectively supplying to said control wires current of one or the other relative polarity, a circuit controlled by a neutral contact of the switch control relay and by the neutral contact of the indication relay for energizing the winding of the switch control relay from said control wires, an auxiliary polarized relay having its winding constantly connected to said control wires, a circuit controlled by a polar contact of said auxiliary relay and by a polar contact of said switch control relay for also energizing the winding of the switch control relay from said control wires, and a lock relay governed by traffic conditions in the vicinity of the switch and controlling the circuit of the winding of the switch control relay.
9. In a switch control system, in combination, a railway track switch movable between a normal and a reverse position, a motor for moving said switch, a polarized switch control relay having polar contacts which when the relay winding is energized with current of normal relative polarity are moved to their normal position and condition the motor to move the switch to the normal position and when the relay winding is energized with current of reverse relative polarity said polar contacts being moved to their reverse position to condition the motor to move the switch to its reverse position, said relay having a neutral contact which is picked up when the relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by a neutral contact of the switch control relay and by the neutral contact of the indication relay for energizing the winding of the switch control relay from said control wires, a circuit controlled by a polar contact of said switch control relay for also energizing the winding of said switch control relay from said control wires, means operative when said polar contact is in its normal position to permit flow of current of normal polarity only in the circuit controlled by said polar contact, and means operative when said polar contact is in its reverse position to permit flow of current of reverse polarity only in the circuit controlled by said polar contact.
10. In a switch control system, in combination, a railway track switch movable between a normal and a reverse position, a motor for moving said switch, a polarized switch control relay having polar contacts which when the relay winding is energized with current of either polarity and when picked up remaining picked up for a time interval subsequent to interruption of the circuit of the relay winding, a neutral contact of said relay controlling the supply circuit for energizing said motor, said neutral contact when picked up establishing said supply circuit and when released interrupting said supply circuit, the polar contacts of said relay being operative when the relay winding is energized with current of one relative polarity to energize the motor from said supply circuit so as to cause the motor to move the switch to one position, the polar contacts of said relay being operative when the relay winding is energized with current of the opposite relative polarity to energize the motor from said supply circuit so as to cause the motor to move the switch to its other position, an indication relay having a slow releasing neutral contact, means operable when and only when the switch is in either its normal or its reverse position for energizing the winding of said indication relay, a pair of control wires, means for selectively supplying to said control wires current of one or the other relative polarity, a circuit controlled by a neutral contact of the switch control relay and by the neutral contact of the indication relay for energizing the winding of the switch control relay from said control wires, an auxiliary polarized relay having its winding constantly connected to said control wires, a circuit controlled by a polar contact of said auxiliary relay and by a polar contact of said switch control relay for also energizing the winding of the switch control relay from said control wires, and a lock relay governed by traffic conditions in the vicinity of the switch and controlling the circuit of the winding of the switch control relay.

- ing is energized with current of normal relative polarity are moved to their normal position and condition the motor to move the switch to the normal position and when the relay winding is 5 energized with current of reverse relative polarity said polar contacts being moved to their reverse position to condition the motor to move the switch to its reverse position, said relay having a neutral contact which is picked up when the 10 relay winding is energized with current of either polarity and which when picked up remains picked up for a time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by a neutral contact of the switch control relay and by a neutral contact of the indication relay for energizing the winding of the switch control relay from said control wires, 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955
12. In a switch control system, in combination, 5 a railway track switch movable between a normal and a reverse position, a motor for moving said switch, a polarized switch control relay having polar contacts which when the relay winding is energized with current of normal relative polarity 10 are moved to their normal position and condition the motor to move the switch to the normal position and when the relay winding is energized with current of reverse relative polarity said polar contacts being moved to their reverse position 15 to condition the motor to move the switch to its reverse position, said relay having a neutral contact which is picked up when the relay winding is energized with current of either polarity and which when picked up remains picked up for a 20 time interval subsequent to interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by a neutral 25 contact of the switch control relay and by the neutral contact of the indication relay for energizing the winding of the switch control relay from said control wires, said circuit being complete when and only when both of said contacts are released or when both of said contacts are 30 picked up, a circuit controlled by a polar contact of said switch control relay for also energizing the winding of said switch control relay from said control wires, means operative when said polar contact is in its normal position to permit flow of current of normal polarity only in the circuit controlled by said polar contact, 35 and a lock relay governed by traffic conditions in the vicinity of the switch and controlling the circuit of the switch control relay.
11. In a switch control system, in combination, 40 a railway track switch movable between a normal and a reverse position, a motor for moving said switch, a polarized switch control relay having polar contacts which when the relay winding is energized with current of normal relative polarity are moved to their normal position and 45 condition the motor to move the switch to the normal position and when the relay winding is energized with current of reverse relative polarity said polar contacts being moved to their reverse position to condition the motor to move 50 the switch to its reverse position, said relay having a neutral contact which is picked up when the relay winding is energized with current of either polarity and which when picked up remains picked up for a time interval subsequent to 55 interruption of the circuit of the relay winding, an indication relay having a slow releasing neutral contact, means operable when and only when the switch is in either its normal or its reverse position for energizing the winding of the indication relay, a pair of control wires, means for selectively supplying to said control wires current of one or the other relative polarity, a circuit controlled by a neutral 60 contact of the switch control relay and by the neutral contact of the indication relay for energizing the winding of the switch control relay from said control wires, said circuit being complete when and only when both of said contacts are released or when both of said contacts are picked up, a circuit controlled by a polar contact of said switch control relay for also energizing the winding of said switch control relay from said control wires, means operative when said polar contact is in its reverse position to permit flow of current of reverse polarity only in the circuit controlled by said polar contact, 65 and a lock relay governed by traffic conditions in the vicinity of the switch and controlling the circuit of the switch control relay.
13. In a switch control system, in combination, 70 a railway track switch movable between a normal and a reverse position, an electric motor for operating said switch, a polarized switch control relay having neutral and polar contacts controlling circuits for energizing said motor, the neutral contacts being picked up when the relay winding is energized with current of either polarity and when picked up remaining picked up for a time interval subsequent to interruption of the circuit of the relay winding, a neutral contact 75 of said relay controlling the supply circuit for energizing said motor, said neutral contact when picked up establishing said supply circuit and when released interrupting said supply circuit, the polar contacts of said relay being operative 80 when the relay winding is energized with current of one relative polarity to energize the motor from said supply circuit so as to cause the motor to move the switch to one position, the polar contacts of said relay being operative when the relay winding is energized with current of the opposite relative polarity to energize the motor from said supply circuit so as to cause the motor to move the switch to the other position, an indication 85 relay having a slow releasing neutral contact, 90

means operable when and only when the switch is in either its normal or its reverse position for energizing the winding of said indication relay, a pair of control wires, means for selectively supplying to said control wires current of one or the other relative polarity, a circuit controlled by a neutral contact of the switch control relay and by the neutral contact of the indication relay for energizing the winding of the switch control relay 5 from said control wires, a circuit controlled by a polar contact of said switch control relay for also energizing the winding of said switch control relay from said control wires, means operative when said polar contact is in its normal position 10 to permit flow of current of normal relative polarity only in the circuit controlled by said polar contact, and means operative when said polar contact is in its reverse position to permit flow of current of reverse polarity only in the circuit 15 controlled by said polar contact.

14. In a switch control system, in combination, a railway track switch movable between a normal and a reverse position, an electric motor for operating said switch, a polarized switch control relay having neutral and polar contacts controlling circuits for energizing said motor, the neutral contacts being picked up when the relay winding is energized with current of either polarity and when picked up remaining picked up 20 for a time interval subsequent to interruption of the circuit of the relay winding, a neutral contact of said relay controlling the supply circuit for energizing said motor, said neutral contact when picked up establishing said supply circuit and when released interrupting said supply circuit, the polar contacts of said relay being operative when the relay winding is energized with current of one relative polarity to energize the motor from said supply circuit so as to cause the motor to move 25 to one position, the polar contacts of said relay being operative when the relay winding is energized with current of the opposite relative polarity to energize the motor from said supply circuit so as to cause the motor to move to the other position, an indication relay having a slow releasing neutral contact, means operable when and only when the switch is in either its normal or its reverse position for energizing the winding of said indication relay, a pair of control wires, means for selectively supplying to said control wires current of one or the other relative polarity, a circuit controlled by a neutral contact of the switch control relay and by the neutral contact of the indication relay 30 for energizing the winding of the switch control relay from said control wires, said circuit being complete when and only when both of said neutral contacts are picked up or when both of said neutral contacts are released, a circuit controlled by a polar contact of said switch control relay for also energizing the winding of said switch control relay from said control wires, means operative when said polar contact is in its normal 35 position to permit flow of current of normal relative polarity only in the circuit controlled by said polar contact, and means operative when said polar contact is in its reverse position to permit flow of current of reverse polarity only in the circuit controlled by said polar contact.

15. In a switch control system, in combination, a railway track switch movable between a normal and a reverse position, a motor for moving said switch, a retained neutral polarized relay having neutral and polar contacts controlling said

motor, a pair of control conductors, means for selectively supplying to said control conductors current of one or the other relative polarity, a circuit controlled by a polar contact of said relay for energizing the relay winding from said control conductors, means operative when said polar contact is in one position to permit flow of current of one relative polarity only in the circuit controlled by said polar contact, means operative when said polar contact is in its other position to permit flow of current of the other relative polarity only in the circuit controlled by said polar contact, and a circuit controlled by a neutral contact of said relay and by means governed in accordance with the position of the switch for also energizing said relay winding from said control conductors, said circuit being complete when said neutral contact is picked up provided the switch is in either its normal or its reverse position, said circuit also being complete when said neutral contact is released provided the switch is not in either its normal or its reverse position.

16. In a switch control system, in combination, a railway track switch movable between a normal and a reverse position, a motor for moving said switch, a retained neutral polarized relay having neutral and polar contacts controlling said motor, a pair of control conductors, means for selectively supplying to said control conductors current of one or the other relative polarity, a circuit controlled by a polar contact of said relay for energizing the relay winding from said control conductors, means operative when said polar contact is in one position to permit flow of current of one relative polarity only in the circuit controlled by said polar contact, means operative when said polar contact is in its other position to permit flow of current of the other relative polarity only in the circuit controlled by said polar contact, a circuit controlled by a neutral contact of said relay and by means governed in accordance with the position of the switch for also energizing said relay winding from said control conductors, said circuit being complete when said neutral contact is picked up provided the switch is in either its normal or its reverse position, said circuit also being complete when said neutral contact is released provided the switch is not in either its normal or its reverse position, and a lock relay governed by traffic conditions in the vicinity of the switch and controlling the circuit of said relay winding.

17. In a switch control system, in combination, a railway track switch movable between a normal and a reverse position, a motor for moving said switch, a retained neutral polarized relay having neutral and polar contacts controlling said motor to cause the motor to move the switch to one or the other of its positions, the relay polar contacts being moved to their normal position when the relay winding is energized with current of normal relative polarity and being moved to their reverse position when the relay winding is energized with current of reverse relative polarity, a pair of control conductors, means for selectively supplying to said control conductors current of one or the other relative polarity, a circuit controlled by a polar contact of said relay for energizing the relay winding from said control conductors, means operative when said polar contact is in its normal position to permit flow of current of normal relative polarity only in the circuit controlled by said polar contact, means operative when said polar contact is in its reverse position to permit flow of current of reverse relative polarity.

- larity only in the circuit controlled by said polar contact, and a circuit controlled by a neutral contact of said relay and by means governed in accordance with the position of the switch for also 5 energizing said relay winding from said control conductors, said circuit being complete when said neutral contact is picked up provided the switch is in either its normal or its reverse position, said circuit also being complete when said 10 neutral contact is released provided the switch is not in either its normal or its reverse position.
18. In a switch control system, in combination, a railway track switch movable between a normal and a reverse position, a motor for moving 15 said switch, a retained neutral polarized relay having neutral and polar contacts controlling said motor to cause the motor to move the switch to one or the other of its positions, the relay polar contacts being moved to their normal position when the relay winding is energized with current of normal relative polarity and being moved to their reverse position when the relay winding is energized with current of reverse relative polarity, a pair of control conductors, means 20 for selectively supplying to said control conductors current of one or the other relative polarity, a circuit controlled by a polar contact of said relay for energizing the relay winding from said control conductors, means operative when said 25 polar contact is in its normal position to permit flow of current of normal relative polarity only in the circuit controlled by said polar contact, means operative when said polar contact is in its reverse position to permit flow of current of 30 reverse relative polarity only in the circuit controlled by said polar contact, a circuit controlled by a neutral contact of said relay and by means governed in accordance with the position of the switch for also energizing said relay winding.
- 40 45
- 40 from said control conductors, said circuit being complete when said neutral contact is picked up provided the switch is in either its normal or its reverse position, said circuit also being complete when said neutral contact is released provided the switch is not in either its normal or its reverse position, and a lock relay governed by traffic conditions in the vicinity of the switch and controlling the circuit of said relay winding.
19. In a switch control system in combination,

a railway track switch movable between a normal and a reverse position, a motor for moving said switch, a polarized relay having neutral and polar contacts controlling circuits for controlling said motor to effect movement of said switch between its two positions, a pair of control wires, a source of current, means for selectively supplying from said source to said control wires current of one or the other relative polarity, a first circuit controlled by a polar contact of said relay 10 for energizing said relay winding from said control wires, means operative when said relay polar contact is in its normal position to permit flow of current of normal polarity only in said first circuit, means operative when said relay polar 15 contact is in its reverse position to permit flow of current of reverse polarity only in said first circuit, a lock relay governed by traffic conditions in the vicinity of said switch, and a second circuit controlled by said lock relay and through which 20 current of either relative polarity may be supplied from said control wires to the winding of said polarized relay.

20. In a switch control system, in combination, 25 a railway track switch movable between a normal and a reverse position, a motor for moving said switch, a retained neutral polarized relay having neutral and polar contacts controlling circuits for controlling said motor to effect movement of said switch between its two positions, a pair of control wires, means for selectively supplying to said control wires current of one or the other relative polarity, a first circuit controlled by a polar contact of said relay for energizing 30 said relay winding from said control wires, means operative when said relay polar contact is in its normal position to permit flow of current of normal polarity only in said first circuit, means operative when said relay polar contact is in its reverse position to permit flow of current of reverse polarity only in said first circuit, a second circuit for energizing said relay winding from said control wires, said second circuit including a neutral contact of said relay and being complete only when said neutral contact is in its 35 picked up position, and a lock relay governed by traffic conditions in the vicinity of said switch and controlling said second circuit.
